UNITED STATES PATENT OFFICE.

GEORGE TRUBEL, OF CHICAGO, ILLINOIS.

JAR-CLOSURE FASTENER.

1,355,289.

Specification of Letters Patent. Patented Oct. 12, 1920.

Application filed November 24, 1919. Serial No. 340,163.

To all whom it may concern:

Be it known that I, GEORGE TRUBEL, a citizen of the United States, residing at Chicago, in the county of Cook and State of Illinois, have invented certain new and useful Improvements in Jar-Closure Fasteners, of which the following is a specification.

This invention relates to improvements in fastening devices particularly adapted though not necessarily limited in its use for securing in position the closure or cover of jars or the like and one of the objects of the invention is to provide an improved, simple, durable, effective and efficient fastening device of this character which may be readily applied and which embodies flexible members overlapping the closure or cover, one end of each of the members being anchored and the other ends of the members being adapted to interlock with the other member for detachably securing the free ends of the members.

A further object is to provide an improved device of this character adapted to serve as a handle for transporting the jar or receptacle and improved means whereby the strain upon the members caused by the weight of the supported article will tend to cause the fastening members to more securely lock the cover or closure in position, and improved means whereby the said members will be secured against relative longitudinal or slipping movement with respect to each other.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which:

Figure 1 is a view partly in vertical section and partly in elevation of a jar having a fastening device secured thereto constructed in accordance with the principles of this invention and also showing the fastening device in two different positions.

Fig. 2 is a top plan view of Fig. 1 with the fastening devices secured together.

Fig. 3 is a detail perspective view of one of the fastening members.

Referring more particularly to the drawing the numeral 10 designates a receptacle such as a jar or the like having a closure 11 and which closure is provided in its upper face and adjacent its periphery 12 with an upwardly opening recess 13 extending thereabout. The receptacle 10 is provided with ears or lugs 14 preferably formed integral therewith and each is provided with an opening 15 therein. These ears or lugs 14 may be secured in any position upon the outer surface of the receptacle but are preferably spaced a short distance from the top of the receptacle.

The fastening device proper consists of two flexible members 16 and as each of these members is of the same construction and configuration, the description of one will apply equally as well to them both.

The member 16 is provided at one end with a hook shaped portion 17 having an upwardly extending part 18, and which upwardly extending part is of a length which normally projects for a considerable distance above the upper surface of the closure 11. The member 16 is then deflected or bent downwardly as at 19 to form an upwardly extending and downwardly opening loop portion 20 and the member 16 beyond the portion 19 is then deflected upwardly to form a downwardly projecting cam shaped portion or fulcrum 21. The free end of the member 16 is shaped to form a hook 22 at the extremity thereof and the member 16 is of such a length as to project entirely across and beyond the periphery of the closure 11.

In use the members 16 are connected to the receptacle by passing the hook shaped ends 17 through the respective openings 15 of the ears 14 in opposite directions so that when the fastening devices are in the position shown in Fig. 1 and unlocked with respect to each other, they will stand in close proximity. The upwardly extending portions 18 of the members are of such a length that the downwardly opening loop shaped portion 20 will be spaced for some distance above the top of the closure 11 and the cam or fulcrum 21 will enter the open groove 13 adjacent the periphery 12 of the closure 11. When the parts are in this position and in order to fasten the members together pressure is exerted upon the free ends of the

members 16 either individually or simultaneously until the hooked extremities 22 are depressed a sufficient distance that they may be projected under the downwardly opening 5 loop 20 by shifting the members 16 laterally with respect to each other and toward each other. When the hook shaped portions 22 have passed beneath the portions 20 and the members 16 released from their pressure 10 the natural spring of the members will cause the hooks to engage under the portions 20.

With this improved construction it will be manifest that as the free ends of the members are pressed downwardly toward the 15 closure 11 considerable pressure will be exerted upon the portions 21 to form fulcrums for the ends of the members 16 and the pressure exerted upon these fulcrums will force the closure 11 against the top of the receptacle. To release the members pressure 20 may be exerted upon the members adjacent their free ends and preferably directly over the cam shaped portions or fulcrums 21 until the hooks are depressed out of engagement 25 with the members, at which time the members may be shifted laterally to release the hooks. The members may then be swung out of engagement with the closure as will be understood.

The closure 11 is preferably provided with 30 a centrally disposed upwardly opening recess 23 directly beneath the central portions of the members 16 so as to enable the members 16 to be gripped by the hand for transporting the receptacle, and in this event the members 16 will serve as a handle.

In order to insure the proper holding of the members 16 so that they will not slip longitudinally with respect to each other 40 and so that the constant lifting and carrying of the receptacle will not strain the members 16 beyond their usefulness, the downwardly opening eye or loop 20 is provided adjacent the cams or fulcrums 21 so that the hooks 22 45 will engage the portions 19 of the members 16 to lock the members against a longitudinal relative shifting movement.

With this construction it will be manifest that the greater the strain which is exerted 50 upon the members 16 when they are serving as a handle, the greater will be the locking qualities of the fastener because any tendency of the members 16 to shift longitudinally will be arrested by the portions 19 and 55 as the hook shaped ends 22 are forced against these parts 19, it will be manifest that any strain thus caused upon the members 16 will tend to reinforce the fulcrums or cam portions 21 and thereby lock the 60 fastening device more securely.

By constructing the members 16 in the manner herein shown and described, it will be manifest that it is not necessary that they shall be constructed in rights and lefts as

either one of the members 16 may be connected to either one of the ears 14 without impairing the operation or efficiency of the fastener. 65

It will also be manifest that with the present construction there is provided an 70 improved, simple, durable and light fastener which may be readily applied and which may as readily be opened without necessitating the use of any tools or implements.

While the preferred form of the invention 75 has been herein shown and described, it is to be understood that various changes may be made in the details of construction and in the combination and arrangement of the several parts within the scope of the 80 claims without departing from the spirit of this invention.

What is claimed as new is:—

1. A fastening device for covers of jars and the like embodying separate and normally detached overlapping resilient members, means detachably anchoring one end of each of the members to opposite sides of the jar, means at the free end of each member adapted to detachably engage the other member adjacent its point of connection with the jar, each of the members being shaped to form a downwardly opening recess to removably receive the respective second recited means. 95

2. A fastening device for covers of jars and the like embodying overlapping resilient members, means detachably anchoring one end of each of the members to opposite sides of the jar, means at the free end of each member adapted to detachably engage the other member adjacent its point of connection with the jar, each of the members being shaped to form a downwardly opening recess to receive the respective second recited means, a portion of each member adjacent the recess being shaped to form a fulcrum engaging and resting upon the jar cover. 100

3. A fastening device for covers of jars 110 and the like embodying overlapping resilient members, means detachably anchoring one end of each of the members to opposite sides of the jar, means at the free end of each member adapted to detachably engage the other member adjacent its point of connection with the jar, each of the members being shaped to form a downwardly opening recess to receive the respective second recited means, the jar cover being provided 115 with an upwardly opening recess within its edges and adjacent the members to receive the fingers of the hand. 120

4. A fastening device for covers of jars and the like embodying overlapping resilient members, apertured lugs carried by the jar, each of said members having one end shaped to form hook shaped portions each 125

- adapted to detachably engage in one of the lugs, said members adjacent the hook shaped portions being shaped to extend above the cover and being bent back upon itself to form a loop, one wall of the loop being shaped to form a cam or fulcrum adapted to rest upon the cover, the free ends of the members being shaped to form hooks to engage under the respective loops to cause the stress of the members to be exerted upon the fulcrums, the said wall of the loop and the hook coöperating to lock the members against relative shifting movement.
- 15 5. A fastening device for covers of jars and the like embodying overlapping resilient members, apertured lugs carried by the jar, each of said members having one end shaped to form hook shaped portions each adapted to detachably engage in one of the lugs, said members adjacent the hook shaped portions being shaped to extend above the cover and being bent back upon itself to form a loop, one wall of the loop being shaped to form a cam or fulcrum adapted to rest upon the cover, the free ends of the members being shaped to form hooks to engage under the respective loops to cause the stress of the members to be exerted upon the fulcrums, the said wall of the loop and the hook coöperating to lock the members against relative shifting movement, and means permitting the said members when secured in locking relation to serve as a handle whereby the receptacle may be transported.
6. A fastening device for covers of jars and the like embodying overlapping resilient members, means detachably and pivotally connecting one end of each member to the jar, the free ends of said members extending over the cover, hooks at the free ends of the members adapted to detachably engage the other member adjacent its point of connection with the jar, and means adjacent the point of connection of each of the members with the jar forming a fulcrum upon which the respective members are sprung to cause the members to press against the cover.
7. A fastening device for covers of jars and the like embodying overlapping resilient members, means detachably and pivotally connecting one end of each member to the jar, the free ends of said members extending over the cover, hooks at the free ends of the members adapted to detachably engage the other member adjacent its point of connection with the jar, and means adjacent the point of connection of each of the members with the jar forming a fulcrum upon which the respective members are sprung to cause the members to press against the cover, the last recited means being formed in the body of the respective members.
8. A fastening device for covers of jars and the like embodying complementary overlapping resilient members, means detachably and pivotally connecting one end of each member to the jar, the free ends of said members extending over the cover, hooks at the free ends of the members adapted to detachably engage the other member adjacent its point of connection with the jar, and means adjacent the point of connection of each of the members with the jar forming a fulcrum upon which the respective members are sprung to cause the members to press adjacent the cover.
9. A fastening device for covers of jars and the like embodying overlapping resilient members, means detachably and pivotally connecting one end of each member to the jar, the free ends of said members extending over the cover, hooks at the free ends of the members adapted to detachably engage the other member adjacent its point of connection with the jar, means adjacent the point of connection of each of the members with the jar forming a fulcrum upon which the respective members are sprung to cause the members to press against the cover, and means coöperating with the said hooks for maintaining the said members against relative slipping movements.
10. A fastening device for covers of jars and the like embodying overlapping resilient members, means detachably and pivotally connecting one end of each member to the jar, the free ends of said members extending over the cover, hooks at the free ends of the members adapted to detachably engage the other member adjacent its point of connection with the jar, means adjacent the point of connection of each of the members with the jar forming a fulcrum upon which the respective members are sprung to cause the members to press against the cover, and means for holding the said members against relative longitudinal movements.
11. A fastening device for covers of jars and the like embodying overlapping resilient members, each of said members being pivotally connected by one end to the jar, means at the free end of each member adapted to detachably engage the other member adjacent its point of connection with the jar, each of the members being shaped to form downwardly opening recesses to receive the respective second recited means.
12. A fastening device for covers of jars and the like embodying overlapping resilient members, means connecting one end of each of the members to the jar for swinging movement with respect thereto, said mem-

bers adjacent their points of connection with the jar being shaped to extend above the cover and being bent back upon itself to form a loop, one wall of the loop being shaped to form a cam or fulcrum adapted to rest upon the cover; the free ends of the member being shaped to form hooks to engage under the respective loops to cause the

stress of the members to be exerted upon the fulcrum, the said wall of the loop and 10 the hook coöperating to lock the members against relative shifting movement.

In testimony whereof I have signed my name to this specification on this 20th day of November, A. D. 1919.

GEORGE TRUBEL.
